UNITED STATES PATENT OFFICE.

JOSEPH IMBRIANI, OF BROOKLYN, NEW YORK.

KNITTING MACHINE.

Application filed April 3, 1925, Serial No. 20,320, and in Germany March 10, 1925.

This invention relates to knitting machines, and has for its primary object to provide improved means for holding the actuating means for needles against casual movement with respect to the jacquard roller and with relation to the needles, thereby insuring at all times an accurate travel or movement of the needles.

It is another object of the invention to provide a device for the above purpose which is easily applicable to the ordinary jacquard knitting machine without necessitating any material alterations therein.

With the above and other objects in view, the invention consists in the improved knitting machine, and in the form, construction and relative arrangement of its several parts as will be hereinafter more fully described, illustrated in the accompanying drawing, and subsequently incorporated in the subjoined claims.

In the accompanying drawings, I have illustrated a practical embodiment of the invention, but have shown only so much of the knitting machine as is necessary for a clear understanding of my present improvements. In these drawings, wherein similar reference characters designate corresponding parts throughout the several views,—

30 Figure 1 is a detail view of one of the needle actuating members;

Fig. 2 is a sectional view through the needle bed showing the relative arrangement of a needle and its actuating member 35 and the means for restraining said actuating member against independent movement;

Fig. 3 is a similar view showing a slightly modified arrangement, and

40 Fig. 4 is a fragmentary plan view. In the accompanying drawings, for purposes of illustration, I have shown a section of the needle bed 5 upon which a plurality of sliding or reciprocating needles 6 are mounted in spaced grooves or channels 45 formed in the surface of said bed.

There is also arranged for sliding movement in each of the bed channels and in line with the respective needles, a needle actuating member 7 which at one of its ends is provided with a widened head 8 for abutting contact against the end of the needle 6. The shaft of each actuating member 7 extends beyond the needle bed 5 and is adapted to be actuated and moved in one direction 55 by a jacquard roller indicated at 9.

Between the needle bed 5 and the jacquard

roller 9 there is arranged two or more spaced bars 10 extending at right angles to the actuating member 7. These bars may either be grooved at one side thereof as shown at 60 11 in Fig. 2 of the drawings or they may be provided with openings as at 12 in Fig. 3. These grooves or openings receive the respective actuating members 7.

Suitable means is operatively connected 65 with the spaced bars 10 and either manually or automatically actuated for displacing or moving said bars in relatively opposite directions as indicated by the arrows of Fig. 4 of the drawings. Thus, it will be evident 70 that each bar at one side of the openings or grooves therein exerts pressure against one side of the actuating members 7 while the other bar exerts a counteracting pressure 75 against the opposite sides of these actuating members, thus restraining said actuating members against a casual or accidental sliding movement relative to the needle bed which would permit a similar accidental or unintentional movement of the needle 6. In 80 this manner therefore, it will be evident that the heads 8 of the actuating members 7 are at all times retained in abutting contact against the ends of the respective needles so that the latter can in no manner slide independently of the actuating members in the grooves of the needle bed in case of vibration of the machine before the needles are caught by the lock, in which event the needles would be brought outside of the reach 85 of said lock.

From the foregoing description taken in connection with the accompanying drawings, the manner of operation and several advantages of my present improvements will 95 be clearly understood. It will be seen that I have devised a very simple and effective means for preventing accidental or casual shifting movement of the needles in a jacquard knitting machine, and which is of 100 such construction that no radical changes are required in the ordinary jacquard apparatus. I have herein shown an embodiment of the device which I have found entirely satisfactory in practical use, but it will 105 nevertheless be understood that the same results might be obtained by means of other alternative constructions, and I therefore, reserve the privilege of adopting all such legitimate changes in the form, construction 110 and relative arrangement of the several parts as may be fairly embodied within the

spirit and scope of the invention as claimed.

I claim:

1. In combination with the reciprocating needles of a jacquard knitting machine, an actuating element for each needle in line therewith and abutting against one end thereof, and adapted to be operated by the jacquard roller of the machine, and a guide member for said actuating elements extending at right angles to the line of movement thereof and shiftable relative thereto to subject said elements to a restraining influence to prevent their casual or longitudinal shifting movement and thereby also prevent casual shifting movement of the needles from their operative positions.
2. In combination with the reciprocating needles of a jacquard knitting machine, an actuating element for each needle in line

therewith and abutting against one end thereof, and adapted to be operated by the jacquard roller of the machine, and a plurality of spaced bars extending transversely of the line of movement of said actuating elements, each of said bars having guide means for said elements and said bars adapted for relative displacement transversely of the actuating elements and in opposite directions to thereby subject said actuating elements to a restraining influence to prevent their accidental longitudinal shifting movement and thereby also prevent casual shifting movement of the needles from their operative positions.

In testimony that I claim the foregoing as my invention, I have signed my name hereto.

JOSEPH IMBRIANI.
